CLOTHES HANGER

Josephine H. Mullen, Dayton, Ohio

Application October 24, 1946, Serial No. 705,473

5 Claims. (Cl. 223—89)

1

This invention pertains to garment hangers, and more particularly to a form retaining coat or dress support maintaining the garment in distended condition.

In the present disclosure there is contemplated a cage like frame of generally prismoidal shape which is extensible and contractible to agree with garments of different sizes, and adaptable for support of multiple garments and other articles.

The object of the invention is to provide an improved garment hanger construction, which is more convenient in use, having a wide field of application, of strong and sturdy construction and unlikely to get out of repair.

A further object of the invention is to provide a garment hanger structure, having means for supporting furs and other small articles which are not usually suspended from hangers.

A further object of the invention is to provide a convenient depository for moth and other insect repellent or perfumed material.

A further object of the invention is to provide a garment support having the advantageous structural features and the inherent meritorious characteristics and mode of use herein mentioned or their equivalents.

With the above primary and other incidental objects in view as will more fully appear in the specification, the invention intended to be protected by Letters Patent consists of the features of construction, the parts and combinations thereof, and the mode of operation, as hereinafter described or illustrated in the accompanying drawings, or their equivalents.

In the drawing wherein is illustrated the preferred, but obviously not necessarily the only form of embodiment of the invention,

Fig. 1 is a perspective view of an assembled garment hanger embodying the present invention.

Fig. 2 is a top plan view thereof.

Fig. 3 is a perspective view, partly broken away of the hanger including a shelf like support on which furs or small articles may be laid, and within which moth repellent or perfumed materials may be deposited.

Fig. 4 is a similar fragmentary perspective view showing plural garments suspended thereon in separated relation.

Fig. 5 is an end elevation of the assembled hanger.

Fig. 6 is a detail sectional view of one of the hanger bars.

Like parts are indicated by similar characters of reference throughout the several views.

Referring to the accompanying drawings, the 55 board. Omitting the telescopically adjustable

2

hanger forming the subject matter hereof comprises a substantially prismoidal cage like frame, including a medial main rod or bar 1, transversely divided into two relatively adjustable sections, and bifurcated at its opposite ends. The furcations 2—2 of the rod 1 are downwardly inclined in divergent relation. The inclined divergent portions 2—2 at opposite ends of the rod 1 are interconnected in a horizontal plane below the main 10 rod or bar 1 by a pair of parallel spaced rods or bars 3—3. Joined to the extremities of the inclined end members 2 in a horizontal plane below that of the rods 3, are relatively short or stub bars or rods 4—4 parallel with the bars or rods 3—3 and with each other. The arms 4 of each pair are axially aligned, but terminate in spaced relation with the mating arms. The main or medial bar 1 is formed with a medial tubular enlargement 5 within which the extended ends of the rods 1 are telescopically adjustable. Likewise the rods 3—3 are medially divided and telescopically interconnected, whereby the hanger frame as a whole is extensible and contractible to fit garments of different sizes. The medial tubular telescopic section 5 is provided with an upstanding swiveled suspension hook 6. The laterally divergent sides of the hanger frame maintains a coat or dress thereon distended, whereby it will longer retain its proper shape. While a coat or dress is suspended upon the hanger frame and held in distended condition, other garments such as skirts or trousers may be suspended from the parallel bars or rods 3—3 as shown at 7 in Fig. 4. The more widely spaced arms 4—4 maintain the 20 dependent portions of the garments suspended from the rods 3 separated as shown in Fig. 4. The short arms of the frame serve to support a transversely interconnecting fabric shelf like member 8 upon which furs, gloves or other smaller articles 25 may be laid. The short arms 4 project within 30 hem 8a of the fabric shelf 8. Such fabric support 8 is provided with a pocket 9 in which insect repellent material or perfumed substance may be conveniently deposited. The respective telescopically adjustable sections of the rods or bars 1, 3 and 4 may be of tubular form of diameters to 35 easily slide one portion within the other, but for convenience and economy of manufacture they may be of inverted channel shape, and for example transversely fluted as shown in cross section 40 in Fig. 6. Such channel type construction, enables the entire hanger frame to be formed as a pair of unitary telescopically engaging sections stamped from sheet metal or pressed from fiber 45 board. Omitting the telescopically adjustable 50

feature the entire hanger frame may comprise a one piece stamping.

An additional suspension hook 10 may be attached within the cage like structure of the under side of the tubular coupling 5, upon which a supplemental garment hanger may be supported without interference with garments directly engaged with the primary structure.

From the above description it will be apparent that there is thus provided a device of the character described possessing the particular features of advantage before enumerated as desirable, but which obviously is susceptible of modification in its form, proportions, detail construction and arrangement of parts without departing from the principle involved or sacrificing any of its advantages.

While in order to comply with the statute the invention has been described in language more or less specific as to structural features, it is to be understood that the invention is not limited to the specific features shown, but that the means and construction herein disclosed comprise the preferred form of several modes of putting the invention into effect, and the invention is therefore claimed in any of its forms or modification within the legitimate and valid scope of the appended claims.

Having thus described my invention, I claim:

1. A garment hanger, comprising an adjustable cage like structure, including a medial main bar divided into two reversely disposed relatively adjustable terminal sections, a tubular intermediate coupling within which the terminal sections are telescopically adjustable, downwardly divergently inclined bifurcated terminals on the adjustable sections of the medial main bar, additional telescopically adjustable bars interconnecting the furcations of the opposite terminals of the medial main bar in spaced relation therewith and with each other, inwardly directed relatively short stub bars projecting from the furcations in parallel relatively spaced relation with the aforementioned bars and with each other and terminating in separated aligned relation with those attached to the furcations of the opposite end of the structure.

2. An expandible and contractible garment hanger comprising a cage like structure including a plurality of longitudinally disposed terminally interconnected parallel spaced bars arranged in relatively divergent planes and transversely divided into telescopically adjustable sections.

3. A garment hanger including a medial longitudinal rod terminally bifurcated, two series of substantially parallel spaced rods arranged in divergent planes to which the bifurcated rod is common, the furcations at the ends of said common rod interconnecting the parallel spaced rods of each of the series with said common rod.

4. A garment hanger including two divergent series of parallel spaced hanger rods, terminal tie members interconnecting the rods of the respective series into a cage like structure of substantially prismatical form, base members therefor of less length than the structure joined to said terminal tie member, each terminating in spaced aligned relation with opposing base members.

5. A garment hanger comprising two divergent series of terminally interconnected parallel spaced hanger rods comprising a cage like structure of prismatical form including two relatively short base rods of each series terminating in aligned spaced relation with each other, and a transversely arranged supporting shelf supported upon the short aligned base rods of the respective series.

JOSEPHINE H. MULLEN.
